CLAIM

The ornamental design for a mounting rail, as shown and described.

DESCRIPTION

FIG. 1 is a perspective view taken from a top, front, left side of a mounting rail according to our design;

FIG. 2 is a perspective view taken from a bottom, rear, right side thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a cross-sectional view thereof taken through line 9-9 of FIG. 7;

FIG. 10 is a cross-sectional view thereof taken through line 10-10 of FIG. 1; and,

FIG. 11 is a cross-sectional view thereof taken through line 11-11 of FIG. 8.
